UNITED STATES PATENT OFFICE.

EUGENE T. TURNER, OF DAVENPORT, IOWA, ASSIGNOR, BY MESNE ASSIGNMENTS, TO AMERICAN PLAYER ACTION COMPANY, OF NEW YORK, N. Y., A CORPORATION OF NEW YORK.

TRACKER-BOARD FOR PIANO-PLAYERS.

1,199,129.

Specification of Letters Patent. Patented Sept. 26, 1916.

Application filed September 22, 1911. Serial No. 650,825.

To all whom it may concern:

Be it known that I, EUGENE T. TURNER, a citizen of the United States, residing at Davenport, in the county of Scott and State 5 of Iowa, have invented a new and useful Tracker-Board for Piano-Players, of which the following is a specification.

My invention relates to improvements in piano players in which a perforated music 10 sheet is caused to pass over a series of apertures connected with the pneumatics for moving the piano action so as to cause the opening and closing of the apertures thereby controlling the pneumatics. The apertures 15 are uniformly arranged side by side in a member usually termed a "tracker board", and it is obvious that it is important that the perforations in the music sheet should come squarely over or track with the proper 20 apertures in the tracker board.

While there are already upon the market various devices for adjusting the roll to the tracker board, they are not always effective because of the unequal expansion or contraction 25 of the music sheet, or from some other agency which affects portions of the music roll unequally.

The objects of my invention are, first, the provision of a tracker board having an auxiliary wind compartment with apertures 30 therein controlled by the music sheet and a pneumatic connected with said auxiliary wind compartment for shifting the relative position of the tracker board and music sheet; second, the provision of a longitudinally 35 movable tracker board which may be easily shifted to secure a proper relation to the music sheet; and, third, the provision of simple means for automatically shifting said 40 tracker board.

The novel features of construction are pointed out in the claims at the end of this specification.

I secure the above objects by means of the 45 mechanism illustrated in the accompanying drawings, in which,—

Figure 1 is a front elevation of my invention partially in section; Fig. 2 is an end elevation of the bellows for the pneumatics; 50 and Fig. 3 is a detail of a modified form of tracker bar having an aperture leading to the auxiliary chamber which co-acts with the edge of a music sheet. Fig. 4 is an enlarged portion of Fig. 1.

Similar reference numerals refer to similar portions throughout the several views.

The reference numerals 1 and 2, designate side bars of a spool frame in which are journaled, one above the other, a lower driven spool, 3, upon which the music sheet 60 is wound during the playing of the piece, and an upper spool, 4, which originally contains the music sheet, and from which it is wound upon the spool, 3, as the piece is played. Suitable mechanism (not shown 65 and forming no part of my present invention) is provided for driving the spool, 3, and for rewinding the sheet upon the spool 4 after the piece has been played.

In the side bars, 1 and 2, between the 70 bearings of the spools, 3 and 4, are provided pairs of bearings, 5, 5, and 6, 6, which align with each other. These bearings, I find, may be very satisfactorily made of felt or other similar material.

My tracker board, 7, has provided upon the ends thereof the pairs of rods, 8, which extend respectively into the bearings, 5, 5, and 6, 6. It will be perceived that this arrangement will permit a considerable longitudinal shifting of the tracker board. The tracker board is located so that the sheet 80 passing from the spool 4 to the spool 3 will contact its forward face, and the double end bearings will prevent the tracker board 85 from being twisted by the action of the sheet.

The tracker board is provided with the usual set of note apertures, 9, which are connected in the usual manner by means of rubber tubes (not shown) with the piano action 90 pneumatics. Above the note apertures in the tracker board I provide an auxiliary channel or wind compartment, 10, which runs longitudinally throughout the portion of the tracker board which will be adjacent 95 the music sheet. Above each note aperture I have provided a smaller aperture, 11, extending into the auxiliary compartment which is so located as to be partially uncovered when the perforations in the music 100 sheet are properly tracking.

Upon the outer face of the side bar, 1, I provide a pneumatic which is constructed as follows:—A rectangular casing, 12, having a vacuum chamber, 13, therein is secured to said side bar. In the lower wall of the casing, 12, is a diaphragm chamber, 14, which is separated from the vacuum cham-

ber by a diaphragm, 15. A small duct, 16, establishes a communication between the vacuum and diaphragm chambers, and the opening of this into the duct 16, is covered 5 by a piece of parchment or other suitable material, 17, in which there is a reduced opening or bleed hole, 18. In the upper wall of the casing, 12, is a passageway, 19, leading to the atmosphere. The passageway, 19, is provided with annular valve seats, 20 and 21, near its bottom and top, and valves, 22 and 23, which seat respectively upon the valve seats, 20 and 21, are mounted upon a valve stem, 24, which extends downwardly into contact with the diaphragm, 15. A bellows, 25, is secured to the outer wall of the casing, 12, and a lateral passage, 26, connects the said bellows with the passageway, 19, at a point between the 10 valve seats, 20 and 21. A flexible tubing, 26, leads from the diaphragm chamber, 14, to the auxiliary channel or wind chest, 10, in the tracker board, 7, and other suitable piping, 27, connects the wind chest, 13, with 15 mechanism for establishing a vacuum (not shown).

The upper one of the rods, 8, is extended through the side bar, 1, and beyond the movable member of the bellows, 25. A collar, 28, 20 is secured upon this rod, 8, by means of a set screw, 29, and a coiled spring, 30, is provided about said rod between its bearing, 5, and the collar, 28, to hold the said rod and the tracker board yieldingly as far to the left 25 as possible. An arm, 31 extends laterally from the movable member of the bellows, 25, and in the arm, 31, is a slot, 32, through which extends the extended rod, 8. The outer end of the rod, 8, is threaded, and upon 30 the threaded portion is screwed a nut, 33. I have provided a felt washer, 34, between the nut, 33, and the arm, 31.

It will now be seen that when the air is exhausted from the bellows, 25, the rod, 8, 45 and the tracker board, 7, will be pressed to the right through the action of the arm, 31, upon the nut 33 against the action of the spring, 30. Each regulating aperture slightly overlaps the right hand edge of its note aperture, as shown by the dotted line 9^a in Fig. 4. When a note properly approaches a note aperture it will uncover a part of the small aperture, 11, just above the particular note 50 aperture.

55 The passage of air through the tracking apertures 11, when their aggregate open area is greater than that of the bleed hole 18 will cause an increased pressure in the diaphragm chamber 14. When the aggregate area of the openings through the apertures 11 is less than that of the bleed hole 18 there will be a reduction of the pressure or volume of air in the diaphragm chamber 14. The air is constantly passing to the diaphragm chamber 14 and thence through the

bleed hole into the vacuum chamber 13 so that this chamber is a pneumatic with a port of fixed open area communicating with the suction chamber, so that there is a continuous flow of air through such pneumatic 70 and port in all positions of such pneumatic (that is whether the diaphragm 15 is raised or lowered) when the sheet is tracking normally; and the main pneumatic 25 and spring 30, by their influence on the position 75 of the tracker bar, cause a variation in pressure of air flowing through the continuous pneumatic or vacuum chamber 14. An increased pressure in the chamber 14 tends to cause the lifting of the valve and the collapsing of the main pneumatic 25 and a movement of the tracker bar to the right, reducing the area of the openings through the apertures 11. When the aggregate open area 80 through such apertures becomes less than 85 that of the bleed hole 18 suction in the diaphragm chamber is increased and the valve is lowered to admit air into the main pneumatic 25, whereupon the spring 30 acts to shift the tracker bar to the left so as to increase the open area through the apertures 11. This results in constantly maintaining the tracker in substantially exact relation to the apertures in the music sheet and holding it balanced between the action of the spring 95 in one direction and of the main pneumatic 25 (under control of the diaphragm chamber) in the other direction. The control of the apparatus by a continuous flow of air is not claimed broadly in the present application 100 being covered by a co-pending application, Serial No. 695,511, filed May 6, 1912.

In Fig. 3, I have illustrated a modification of my tracker board in which I have provided an aperture 11^a to co-act with the 105 edges of the music sheet instead of the apertures 11, to co-act with the edges of the note perforations therein.

Having thus described my invention what I claim as new; and desire to secure by Letters Patent, is:—

1. In a piano player, a tracker board having an auxiliary wind compartment therein and having a plurality of apertures into said auxiliary compartment which are each only 115 partially uncovered by the note apertures in the normal position of the music sheet, yielding means tending always to cause relative movement in one direction between the music sheet and the tracker board, and 120 means for causing such relative movement in the opposite direction connected with and controlled by the pressure in said auxiliary compartment.

2. In a piano player a tracker board having note apertures therein adapted to coact with the note apertures in the music sheet, an auxiliary wind compartment running longitudinally thereof and tracking-control apertures opening therefrom and each adapted 125 130

- to be partially uncovered by the note apertures of the sheet in the normal position of the latter, yielding means tending always to cause relative movement in one direction between the music sheet and the tracker board and means for causing such relative movement in the opposite direction connected with and controlled by the pressure in said auxiliary compartment.
3. In a piano player a tracker board having note apertures therein adapted to coact with the note apertures in the music sheet, an auxiliary wind compartment in the tracker board and running longitudinally thereof and a tracking-control aperture from said compartment adapted to be partially uncovered by the sheet in the normal position of the latter, yielding means tending always to cause relative movement in one direction between the music sheet and the tracker board and means for causing such relative movement in the opposite direction connected with and controlled by the pressure in said auxiliary compartment.
4. In a piano player, a longitudinally moving tracker board, a continuously acting spring engaging a part thereof and pressing the same yieldingly in one direction, a pneumatic device also engaging a part of said tracker board and adapted when collapsed to cause a movement thereof in the opposite direction, a vacuum chamber, a valve between said vacuum chamber and said pneumatic, said tracker board having a tracker control aperture adapted to be partially uncovered in the normal position of the sheet and the opening and closing of which controls the movement of said valve.
5. In a piano player, a member having an aperture therein adapted to be opened or closed by the music sheet and which is partially open in the normal position of the sheet, a pneumatic, a vacuum chamber, a valve between said pneumatic and said chamber, said valve being operated upon an increased opening of said aperture to cause an opening movement of said valve and a closing movement of said aperture, and continuously acting yielding means tending always to cause the opening of said aperture.
6. In a piano player, a longitudinally movable tracker board, an auxiliary aperture therein which is partially open in the normal position of the sheet relatively to the tracker board, a continuously acting spring for moving said board in one direction, a pneumatic, a vacuum chamber, a valve between said pneumatic and said chamber, said valve being controlled by an increased opening of said auxiliary aperture for causing said pneumatic to move said board in the other direction.
7. In a piano player, a tracker board disposed transversely of the music sheet, and having an aperture which is partially open in the normal position of the sheet, continuously acting means for changing the relation of said sheet to said aperture in one direction, a pneumatic, a vacuum chamber, a valve between said pneumatic and said chamber, said valve being controlled by the relation of said sheet to said aperture for causing said pneumatic to change said relation in the other direction.
8. A tracker mechanism for piano players, comprising a tracker board having note apertures therein and over which travels a music sheet having note perforations therein and having a tracking aperture which is partially open in the normal position of the sheet, continuously acting yielding means for changing the horizontal relation of said note apertures and tracking aperture in one direction, a pneumatic, a vacuum chamber, a valve between said pneumatic and said chamber, said valve being controlled by the relation of said note apertures to said tracking aperture for causing the pneumatic to change the relation in the opposite direction.
9. A tracker mechanism for piano players, including a tracker board having a line of note controlling apertures and a line of tracking-control apertures each adapted to be partially opened by the note apertures in the music sheet in the normal position of the latter, a common trunk communicating with said tracking-control apertures and pneumatic mechanism communicating with said trunk and adapted to cause a relative movement between said tracker board and the music sheet.
10. A tracker mechanism for piano players including a tracker board having a line of note-controlling apertures adapted to register with the note perforations in the music sheet, said board having also a line of tracking-control apertures each adapted to be partially opened by the note apertures in the music sheet in the normal position of the latter, means for causing a relative movement between said board and said sheet in a direction to open said tracking-control apertures through the note perforations of the sheet and automatic mechanism actuated by the opening of said tracking-control apertures for causing a relative movement in the opposite direction.
11. The combination with a tracker bar containing apertures for effecting sound production and apertures for effecting adjustment, of a music sheet containing perforations, means for carrying said sheet over said tracker, and means operated by the coaction of said perforations with said apertures second named to maintain the registration with said perforations of said apertures first named, said second named apertures being partially uncovered by said music sheet when said perforations are in

correct registration with said first named apertures.

12. The combination of a music sheet containing perforations, with a tracker mechanism containing a set of apertures coacting with said perforations to effect the production of musical sounds, and pneumatic mechanism for maintaining registration between said perforations and apertures, said pneumatic mechanism comprising a duct having an aperture controlled by said sheet and adapted to register with perforations aforesaid, a pneumatic having a duct connected therewith, a suction duct communicating with said duct first named by a "bleed" aperture, and automatically operated valve mechanism for connecting said second duct with the atmosphere and with said suction duct.
13. The combination of a music sheet containing perforations, with a tracker mechanism containing a set of apertures coacting with said perforations to effect the production of musical sounds, and mechanism comprising a set of apertures adapted to com-

municate with perforations aforesaid for automatically maintaining registration between said perforations and apertures, said mechanism comprising a rod and means for adjusting the effective length of said rod. 30

14. A tracker bar for playing attachments for musical instruments making use of a perforated music sheet, said tracker bar being provided with the usual ducts for register with the note slots in a music sheet 35 passed over the tracker and also having additional openings within the paths of the note slots across the tracker when such note slots are in proper register with the tracker ducts, one edge of each of said additional 40 openings being adjacent to one edge of one of the usual ducts and said additional openings being in alinement lengthwise of the tracker, substantially as set forth.

In testimony whereof, I have hereunto set 45 my hand in the presence of two witnesses.
